RECTIFIER FOR REFRIGERATING SYSTEMS

Curtis C. Coons, North Canton, Ohio, assignor to
The Hoover Company, North Canton, Ohio, a
corporation of Ohio

Application August 8, 1936, Serial No. 94,935

25 Claims. (Cl. 62—119.5)

This invention relates to continuous absorption refrigerating systems and more particularly to the combination therewith of a liquid dividing or apportioning device for dividing and distributing liquid between two or more portions of such systems.

Continuous absorption systems customarily operate under relatively high internal pressures, and for this and other reasons it is found expedient to seal the same hermetically and to avoid the use of shafts, valve stems and other movable elements passing through the side wall of the apparatus. Because of these facts much difficulty has been experienced heretofore in controlling, regulating, circulating and apportioning liquid working mediums present in these systems as is desired or advantageous for best operation. The problem is augmented considerably because of the small volume of liquid flowing, and the wide variation in the rate of flow under the different conditions of operation normally encountered.

For example, an absorption refrigeration system of the type herein disclosed constructed to refrigerate a household refrigerator cabinet of average size produces approximately one quart of liquid refrigerant per hour. It will therefore be evident that the stream of liquid refrigerant flowing from the condenser is very small, and more in the nature of a trickle than a stream of liquid.

Likewise, the absorption liquid stream flowing between the boiler and absorber of such a system flows at the rate of approximately one gallon per hour. Hence, even the absorption solution flow, while considerably greater than the refrigerant liquid flow, is so small as to be properly termed a trickling flow.

In view of the foregoing, it will be readily appreciated that the problem of dividing or apportioning the liquid refrigerant or the absorption solution uniformly and in any desired ratio is a difficult one—particularly if the use of orifices, restrictors, and complex devices is to be avoided.

It is accordingly a principal object of this invention to provide a continuous absorption refrigeration system having means for apportioning liquid within the system between a plurality of parts thereof. More specifically, it is an object of the invention to divide a stream of liquid in a desired ratio and to distribute the divided liquid to different parts of the system.

Another object of the invention is to provide an absorption refrigeration apparatus with an unrestricted means for dividing accurately a body of liquid into a plurality of bodies in re-

sponse to a flow of the first mentioned body and irrespective of wide variations in the rate of supply to the dividing means.

Another object of the invention is the provision of self-contained and automatically operable means for apportioning liquid refrigerant of a refrigeration system between a plurality of places of evaporation, as for example, an evaporator vessel and a reflux rectifier vessel.

A still further object is to provide means for returning a predetermined portion of liquefied refrigerant into the presence of hot refrigerant vapor for the purpose of rectifying the same. More particularly, it is an object to provide a new and improved rectifier operating adiabatically or with substantially no gain or loss of heat.

Other objects and advantages reside in certain novel features of the arrangement and the construction of parts as will be apparent from the following description taken in connection with the accompanying drawing in which:

Figure 1 is a diagrammatic view, partly in vertical section, of a continuous absorption refrigerating system constructed in accordance with the present invention.

Figure 2 is a vertical cross-sectional view, somewhat enlarged of the liquid divider employed in the arrangement of Figure 1, and

Figure 3 is a transverse cross-sectional view of the liquid divider shown in Figure 2, the view being taken on the line 3—3 thereof.

Referring to the drawing in detail and first to the arrangement in Figure 1, it will be seen that a continuous absorption refrigerating system is there shown comprising as principal parts, a boiler B, a rectifier designated generally R, an evaporator E and an absorber A. These principal parts are connected by various conduits to form the complete refrigerating system as will be described hereinbelow.

The boiler B may consist of two chambers 11 and 12, the chamber 11 being connected to the vertical pipe 13 (which includes the rectifier) by means of a vapor lift pump conduit 14.

The vertical cylindrical portion 13 of the boiler system is connected at its lower end to the chamber 12 and is provided with a number of baffle plates 15 therein. Above the baffle plates suitable filling material, such as small metal cylinders, chain or other means for providing extended surface, is provided, as shown at 16 and most of the rectification takes place on this material. The top of the rectifier R is connected to the condenser C by means of the refrigerant conduit 17 and as the refrigerant liquefies in the

condenser C, it flows through the conduit 18 into the liquid divider or apportioning chamber 19.

The liquid divider may be so constructed as to proportion the amount of liquid, or divide it into streams. To this end the small pivoted dish or proportioning device 20 is mounted for movement upon the pivot 21.

As best shown in Figure 2, the dividing device is sub-divided into two chambers of unequal size by a vertical partition 22. It will, of course, be apparent that the two chambers may be of equal or unequal size, as may be found most advantageous in obtaining a desired operation of the system or any part thereof. When the divider device is to be employed in the manner illustrated in the accompanying drawing as one manner of applying the invention, the receiving cup on the right of the partition is preferably somewhat smaller than the one on the left. With receptacle 20 in the position shown in Figure 2, liquid will drop from conduit 18 into the right hand cup until the weight of the liquid so collected is sufficient to counter-balance the receptacle thereby discharging the collected liquid into the right hand compartment in chamber 19. The liquid then flows through conduit 23 to rectifier R. Pivot 21 in chamber 19 forms a dividing partition and prevents liquid discharged into one chamber from flowing to another chamber.

While receptacle 20 is tilted to the right, condensate will drip from conduit 18 into the left hand cup where it is stored until a sufficient quantity has collected to tilt the receptacle counterclockwise, whereupon the stored liquid is discharged and flows through conduit 24 into evaporator E. Receptacle 20 may be provided with counter weights as shown in Figure 2, or may be so constructed as to maintain the proper balance and to enable the desired quantity of liquid to be collected before it is discharged for flow to the particular vessel for which it is intended. It will also be understood that the liquid receiving cup may be relatively small or relatively large. In this way, the time interval between successive discharges may be made relatively long or relatively short.

The evaporator E is connected to the absorber A by means of two inert gas conduits 25 and 26 which may be in heat exchange relation. One of these may include an inert gas fan or circulator 27 adapted to be driven by an electric motor 28 as illustrated.

The absorber is connected to the boiler by means of liquid conduits 29 and 30 which may be in heat exchange relation and which may be connected in accordance with known practice.

In the arrangement illustrated, absorption liquid is lifted from the right hand chamber 11 of the boiler by vapor lift pump 14 into the vertical cylinder 13 above the lowermost baffle plates 15 therein and thence flows by gravity downwardly through the cylinder 13, the left hand chamber of the boiler, the conduit 29 into the top of the absorber. After trickling downwardly over baffle plates or the like in the absorber, the liquid flows back to the boiler by gravity through the conduit 30.

The system may be charged with any of the commonly employed working mediums for absorption refrigeration systems such as ammonia, water and nitrogen in accordance with known practice.

The entire boiler system, that is the boiler chambers 11, 12 and the cylinder 13 together with a portion of the pipe 17 above the rectifier

may be encased in the insulation as indicated at 31. Heat may be applied to the boiler chambers 11 and 12 by means of some suitable source as the electric cartridge heaters illustrated at 32.

5 In the arrangement hereinabove described it will be clear that the divider device has been employed to apportion liquid refrigerant between an evaporator and an adiabatic reflux rectifier. The condensate discharged by condenser C is 10 automatically divided and a predetermined portion returns to the rectifier through conduit 23. This reflux condensate functions to remove the absorption liquid vapor from the refrigerant vapor passing upwardly through rectifier R and over material 16 in a highly efficient manner as 15 will be readily apparent from the fact that the amount of condensate returned may be carefully controlled and proportioned to maintain the optimum condition. The rectifier is surrounded by insulation and accordingly operates substantially adiabatically. The portion of condensate not returned to the rectifier flows to the evaporator where it is utilized to produce refrigeration.

From the foregoing description, it will be apparent that I have provided a novel device for dividing liquid in a refrigeration apparatus and for directing the same to a plurality of vessels within the system in equal or unequal portions as desired. The dividing mechanism proper may 20 be and preferably is entirely housed within the system, and operates automatically in accordance with either a uniform or a rapidly fluctuating flow to divide such flow in any predetermined manner. Furthermore, the device inherently 25 functions to direct a predetermined quantity of liquid to each of a plurality of vessels intermittently and at time intervals dependent upon the proportions and mass of the liquid receiving cups of the divider. While the divider has been shown 30 as connected to the condenser discharge conduit, it will be understood that the device may be positioned anywhere in a refrigeration system at which its function may be found useful.

While only one embodiment of the invention 35 has been shown and described herein it is obvious that various changes may be made in the arrangement and construction of parts without departing from the spirit of the invention or the scope of the annexed claims.

50 I claim:

1. In an absorption refrigerating system, having a boiler system and a condenser, a reflux rectifier comprising a vessel adapted to receive refrigerant vapor and absorption liquid vapor from the boiler system, means for insulating said vessel and means for conveying a portion of the refrigerant condensed in the condenser to said vessel to aid in the removal of the absorption liquid vapor from the refrigerant vapor therein.

60 2. In an absorption refrigerating system, having a boiler system and a condenser, a reflux rectifier comprising a vessel adapted to receive refrigerant vapor and absorption liquid vapor from the boiler system, means for insulating said vessel and means for conveying a portion of the refrigerant condensed in the condenser to said vessel to aid in the removal of the absorption liquid vapor from the refrigerant vapor therein, said last mentioned means including a tiltable liquid divider positioned below the condenser and adapted to divide the liquid supplied thereto into two streams.

65 3. In combination with a reflux rectifier, means for liquefying vapor passing through said rectifier, and a liquid divider for returning a definite

portion only of a stream of said liquefied vapor to said rectifier, said liquid divider comprising a casing, a pivot therein and a dish having two cups tiltably mounted on said pivot.

4. In combination with a reflux rectifier, a liquid divider arranged to return a definite portion of a stream of liquid to said rectifier, said liquid divider comprising a casing, a pivot therein and a dish having two cups tiltably mounted on said pivot, said cups having different volumes whereby the portion of liquid supplied to said rectifier is other than half of the stream of liquid supplied to the liquid divider.

5. That improvement in the art of refrigeration by means of an absorption system comprising a boiler, a reflux rectifier, a condenser and an evaporator in communication with one another, which consists in generating refrigerant vapor in the boiler, passing the vapor through the rectifier and to the condenser to be condensed, and returning a minor portion of said condensate to the rectifier in an unrestricted path of flow to condense absorbent vapor.

6. That improvement defined in claim 5 which includes means in the condensate return means to prevent the by-passing of refrigerant vapor around the condenser.

7. That improvement defined in claim 5 in which said condensate return means includes a tiltably mounted liquid dividing means automatically operable to divide the condensate delivered by the condenser into two unequal portions.

8. An absorption refrigeration apparatus of the type containing a condensable refrigerant medium and a liquid absorbent medium therefor, characterized by the fact that said apparatus is provided with movable means operable to automatically divide one of said mediums into two streams, and a casing comprising a part of said apparatus and enclosing said movable means.

9. An absorption refrigeration apparatus of the type containing a refrigerant medium and having a condenser and an evaporator means in communication therewith, characterized by the fact that said apparatus is provided with movable means sealed within the apparatus automatically operable to divide liquid refrigerant delivered by the condenser into two portions, and alternately delivering one of said portions to said evaporator means.

10. An absorption refrigeration apparatus of the type containing a refrigerant, an absorbent therefor, and an inert pressure equalizing medium, said apparatus including a condenser and at least one evaporator section in communication therewith, and means sealed within said apparatus operable to supply liquid refrigerant intermittently from said condenser to said one evaporator section, said refrigerant supply means being so constructed and arranged as to operate at frequent intervals while substantially continuous refrigeration takes place in said apparatus.

11. That improvement in the art of refrigeration by means of an absorption refrigeration apparatus having a refrigerant condenser and at least one evaporator section in communication therewith, which comprises providing means for directing condensate from said condenser to said evaporator section for a period of time and thereafter to another portion of said apparatus for a period of time.

12. That improvement in the art of refrigeration

by means of an absorption refrigeration apparatus having a refrigerant condenser and at least one evaporator section in communication therewith, which comprises providing means sealed within the apparatus automatically operable to divert condensate from said condenser into said evaporator section for a period of time and thereafter into another part of said apparatus for a period of time.

13. That improvement in the art of refrigeration by means of an absorption refrigeration apparatus including a boiler assembly, a condenser, at least one evaporator section, and an absorber in circuit, which includes condensing gaseous refrigerant derived from said boiler assembly in said condenser, and periodically diverting said condensate first to said evaporator section where at least portions of the same are vaporized by the absorption of heat, and thereafter to another part of said apparatus where at least portions of the same are vaporized by the absorption of heat.

14. That method of operating a continuous absorption refrigerating apparatus of the type having a boiler assembly, a condenser, an evaporator and an absorber in circuit, and charged with a refrigerant, an absorbent therefor and a pressure equalizing medium, and in which the boiler assembly and substantially all that portion of the circuit between said assembly and the condenser is enclosed by heat insulation material, which method comprises diverting condensate first to a vaporizing zone to produce refrigeration and then to a zone containing hot refrigerant and absorbent vapors where at least a portion of the condensate is vaporized by the heat of condensation of absorbent vapor.

15. That method of separating a mixture of hot refrigerant vapor and absorbent vapor having a higher boiling point than the refrigerant vapor, which includes condensing the refrigerant vapor derived from said mixture, alternately directing the condensate first into the presence of an inert gas where the condensate evaporates to produce refrigeration, and then into intimate contact with said mixture of vapors at a point where the same are in contact with a liquid solution of the refrigerant and absorbent medium whereby the absorbent vapor condenses and additional refrigerant vapor is produced by the heat of condensation of the absorbent vapor.

16. The method of claim 15 in which the separation of refrigerant vapor and absorbent vapor is produced adiabatically.

17. An absorption refrigeration system of the type described, said system comprising a boiler assembly, a condenser, an evaporator assembly, and an absorber in circuit, and containing a condensable refrigerant fluid, said circuit comprising at least two parallel liquid passageways, and unrestricted means within said system operable to divide liquid refrigerant between said parallel passageways, said means including a movable element positioned in the path of flow of liquid refrigerant and actuated by a flow of said refrigerant.

18. An absorption refrigeration system of the type described, said system comprising a boiler assembly, a condenser, an evaporator assembly and an absorber in circuit and containing a refrigerant fluid and an absorbent fluid therefor, said circuit comprising at least two parallel liquid passageways, and means within said system operable to divert one of said fluids into first

one and then into the other of said passageways, said means including a movable element positioned in the path of flow of said one fluid and actuated by a flow of said one fluid.

19. An absorption refrigeration system of the type having a boiler assembly, a condenser, an evaporator assembly and an absorber in circuit and containing a refrigerant fluid and an absorbent fluid, characterized by the fact that said circuit provides at least two parallel fluid passageways, and means sealed within said system and automatically operable to divert one of said fluids to one of said passageways for a period of time and thereafter to another of said passageways for a period of time.

20. An absorption refrigeration system of the type having a boiler assembly, a condenser, an evaporator assembly and an absorber in circuit, and containing a refrigerant fluid and an absorbent fluid, characterized by the fact that said circuit provides a plurality of parallel fluid passageways, and means automatically operable to divert refrigerant fluid in liquid form to first one of said passageways for a period of time and thereafter to another one of said passageways, at least one of said passageways including said evaporator assembly.

21. A liquid condensate divider for use in a refrigeration system comprising a vessel adapted to be connected to a condenser in an upper portion thereof, a partition dividing the bottom of said vessel into two chambers each of which has a liquid discharge opening, and a dividing device tiltably mounted on said partition beneath said condenser connection to receive liquid therefrom, and means dividing said device into

two liquid receptacles such that when enough liquid flows into one receptacle said device will overbalance and discharge to one of said chambers, and after sufficient liquid has flowed into the other receptacle the device will tilt in the opposite direction and discharge into the other of said chambers.

5 22. A liquid condensate divider as recited in claim 21 in which the dividing device is so constructed that less liquid is required to tilt the 10 some in one direction than in the other.

15 23. A hermetically sealed refrigeration system of the absorption type and having a liquid supply conduit and two liquid discharge conduits therefor and forming a part of said system, characterized by the provision of a tilttable device at the junction of said supply and discharge conduits and automatically operable in response to the flow of liquid in said supply conduit to divide the liquid between said discharge conduits.

20 24. A hermetically sealed refrigeration system of the absorption type and having a liquid supply conduit and a plurality of liquid discharge conduits therefor and forming a part of said system, characterized by the provision of a tilttable device at the junction of said supply and discharge conduits and automatically operable to divert fluid from said supply conduit to one 30 of said discharge conduits, and after a period of time to another of said discharge conduits.

25 25. The subject matter of claim 24 characterized by the fact that the period of time during which the fluid is diverted to a given discharge conduit is directly proportional to the rate of flow in the supply conduit.

35 CURTIS C. COONS.
